UNITED STATES PATENT OFFICE.

NIELS ANTON CHRISTENSEN, OF MILWAUKEE, WISCONSIN.

FLUID-PRESSURE HOIST.

SPECIFICATION forming part of Letters Patent No. 657,332, dated September 4, 1900.

Application filed August 21, 1899. Renewed June 25, 1900. Serial No. 21,502. (No model.)

To all whom it may concern:

Be it known that I, NIELS ANTON CHRISTENSEN, a resident of Milwaukee, in the county of Milwaukee and State of Wisconsin, have invented certain new and useful Improvements 5 in Fluid-Pressure Hoists and the Like, of which the following is a specification.

My invention relates to fluid-pressure hoists and the like; and one of its objects is to provide novel, simple, and efficient mechanism for controlling the pressure to and from the cylinder.

Another feature of my invention consists in an air-cushion formed at one end of the cylinder to prevent violent contact between the top cover and the piston on its full upward or inward stroke and also in a safety device in combination with other parts and comprising a check or non-return valve in the 15 main air-pipe to prevent backflow of pressure through the reservoir-pipe, and thereby prevent dropping of the load in case such pipe should burst or part while the controlling-valve is in application position and not in lap.

25 In the drawings, Figure 1 is an elevation of my hoist and controlling-valve; Fig. 2, a sectional elevation thereof. Figs. 3, 4, 5, and 6 are details of the controlling-valve, the section shown in Fig. 3, except as to the valve 18, 30 being taken on the angular line 3 3 of Fig. 4 and the section of such valve 18 being taken on line 3 of Fig. 6; and Fig. 7, an enlarged detail view of the spring 25.

The cylinder 1 has the usual top cover or 35 cap 2, a bottom cover or cap 3, a piston 4, and stuffing-box 5. The cylinder is provided with one or more ports 6 near its top end, and the piston is of sufficient length so that upon full travel it will close said port or ports, and 40 thereby an air-cushion will be formed at the top of the cylinder to prevent violent contact between the piston and the cover.

Compressed air is supplied from a reservoir or other suitable source to the main air-pipe 45 7, which is provided with a check or non-return valve 8, located in the air-pipe, preferably near the controlling-valve. This check-valve permits free flow of air toward the controlling-valve, but prevents its return, where- 50 by the pressure already admitted to the cylinder is maintained therein even though the controlling-valve may be in application posi-

tion. The main air-pipe communicates with a port or passage 9 in the cover 3, which is also provided with a cylinder port or passage 55 10, passing therethrough and entering the cylinder below the piston. The function of the controlling-valve is to govern the admission and release of pressure into and from the cylinder through the cylinder-port 10. 60

The controlling-valve consists, in general terms, of a base or valve-seat 11 and a bonnet or casing 12, within which operates a disk valve. This seat is secured to the cover 3 by bolts or otherwise, and the same has three 65 ports or passages 13, 14, and 15, all terminating on the face 16 of the valve-seat. The ports 13 and 14 communicate, respectively, with the ports 9 and 10, the port 13 being the reservoir-port and the port 14 the cylinder- 70 port, while the port 15 is the exhaust-port leading through the seat to the atmosphere. The seat is also provided with a central recess or socket 17. The inner wall of the valve-chamber may have a score or channel 75 12^a, communicating with a passage or recess 13^a, cut on the valve-seat and extending from the port 13. The purpose of such score is to drain away any water or moisture that may form or collect in the chamber or between the 80 very narrow clearance between the valve and the walls of the chamber. Ports 13, 14, and 15 are governed by the disk valve 18, operating in the casing 12 and having an operating- 85 stem 19. The face of this valve is provided with means for connecting any two of the 90 ports, which means may consist, as shown, of two ports 20 and 21, connected by an internal passage 22, or, as is obvious, a single recess may serve the purpose. The valve has 95 a central stem 18^a, received by the socket 17.

Upon one side of the casing or bonnet are arranged similar lugs 23, having holes to receive a pin 24, forming a pivot for a spring 25, whose intermediate portion is coiled 95 around the pin and whose extreme free ends are formed substantially straight and extend around the casing on either side, so as to lie on either side of a projection or lug 26 on the casing, which is located substantially diamet- 100 rically across from the lugs 23. The portions of the ends of the springs between the extreme ends and the coiled portion are curved to correspond with the curvature of the casing.

The valve-stem 19 may be operated by the usual hand chains or ropes, and to this end a valve-lever device is secured to this stem, which lever comprises a hub-piece 27, having diverging lever-arms 28 and 29 and a curved arm or horn 30, extending upwardly intermediate of the lever-arms and engaging between the free ends of the spring. The hub also has projecting hook-shaped arms 31 and 32 to contact with the pivot-pin, whereby a stop is provided for the extreme movements of the levers in the two directions.

The normal or lap position of the disk valve is maintained by the spring, whose free ends 15 keep the horn 30 directly beyond and in line with the projection 26. At this time all the ports are closed and the valve is said to be on lap. By the means shown I secure a position of lap which is absolutely definite, and the 20 valve cannot be changed from this position except by deliberate intent of the operator. When one of the hand chains or ropes attached to the arms 28 and 29 is pulled to rotate the valve to application position, the 25 ports in the face of the valve connect the reservoir-port with the cylinder-port and compressed air is thereupon admitted to the cylinder to operate the piston in the usual manner. The speed of admission may be easily 30 regulated by the fullness of application due to the amount of rotation of the valve whose full movement is limited by contact of one of the hook-shaped arms against the pivot-pin. As the main air-pipe has a check-valve, the 35 compressed air can be kept in the cylinder to hold the load in case of accident to such pipe even while the disk valve is in application position, as just described. The disk valve will be restored to lap position by the spring 40 so soon as the operator releases the lever and the compressed air will be confined in the cylinder. To release the air, the other chain or rope is pulled to rotate the valve in the 45 opposite direction, whereupon the cylinder-port will be connected to the exhaust-port and the cylinder thereby exhausted. The speed or amount of release of the cylinder may thus be easily regulated and the spring 50 will return the valve to a positive lap position immediately upon a release of the hand chain or rope by the operator.

By the use of my invention I provide a valve which is not liable to leak, but is capable of performing its functions in a reliable and efficient manner, and in addition I also provide means whereby a positive and definite lap of the valve is always assured.

While I have shown and described my invention as applied to a vertical hoist, it will be understood that the same may be applied to cylinders and hoists of other types, and consequently I contemplate using my invention wherever applicable.

Although I have described more or less precise forms and details of construction, I do not intend to be understood as limiting myself thereto, as I contemplate changes in form,

the proportion of parts, and the substitution of equivalents as circumstances may suggest or render expedient without departing from the spirit of my invention.

I claim—

1. A fluid-pressure hoist comprising a cylinder, a valve governing the admission and release of pressure to and from the cylinder, and a single spring exerting its tension upon the valve to normally keep it in lap position and to restore it to such position after movement in one direction to application position or after movement in the opposite direction to release position.

2. A fluid-pressure hoist comprising a fluid-pressure-actuated piston traveling in a cylinder, a casing having a valve governing the admission and release of pressure to and from the cylinder and tension mechanism mounted on and extraneous of the casing and co-operating directly with such valve to normally keep it in lap position and restore it to that position after movement to a position on either side of lap position.

3. A fluid-pressure hoist comprising a fluid-actuated piston traveling in a cylinder, a valve governing the admission and release of pressure to and from the cylinder, a stem for such valve, and a spring having its two free ends co-operating directly with such stem and tending to resist movement thereof away from lap position.

4. A fluid-pressure hoist comprising a cylinder having a piston and provided with inlet, exhaust and supply ports, a valve governing said ports by connecting the inlet and supply ports in application position and the inlet and exhaust ports in release position, an operating-stem for the valve provided with an arm or horn and a spring directly engaging such horn and exerting its tension against rotation of the stem.

5. A fluid-pressure hoist comprising a cylinder having a piston and provided with inlet and exhaust ports, a fluid-pressure-supply port, a valve governing said ports, an operating mechanism for such valve, a casing for said valve, and a spring mounted on and extraneous of the casing and bearing against said operating mechanism for normally maintaining the valve in lap position and adapted to automatically restore the same after movement to application position or exhaust position.

6. A fluid-pressure hoist comprising a cylinder having a piston and provided with inlet and exhaust ports and also a supply-port, a valve governing said ports, a casing for said valve, operating mechanism for such valve, and a spring pivoted on the casing and having its ends bearing against such operating mechanism to keep the valve in lap position and restore the same after any movement out of such normal position.

7. A fluid-pressure hoist comprising a cylinder having a piston and provided with inlet and exhaust ports and also a supply-port,

5 a valve governing said ports and having an operating-stem, a casing therefor, a hub secured to the stem and having lever-arms, a projection or horn from the hub intermediate of the arms, and a spring mounted on the casing and having its free ends bearing on either side of such horn to maintain the valve in normal position.

8. A fluid-pressure hoist comprising a cylinder having a piston and provided with inlet and exhaust ports and also a supply or reservoir port, a valve governing said ports and having an operating-stem, a casing therefor having a lug or projection on one side, a pin 10 mounted on the outside of the casing opposite the lug, a spiral spring pivoted to such pin and having its free ends extending on either side of the casing and on either side of such lug, lever-arms secured to the valve-stem and a horn movable with said lever-arms and extending between the ends of such spring.

9. A fluid-pressure hoist comprising a cylinder having a piston and provided with inlet and exhaust ports and also a supply or reservoir port, a valve governing said ports and having an operating-stem, a casing therefor, a coiled spring pivoted on one side of the casing and having its free ends extending substantially parallel across the casing on either side thereof, a hub connected to said valve-stem and having diverging lever-arms and also having a horn extending to between the free ends of the spring whereby the movement of the valve in either direction is against the tension of the spring.

10. A fluid-pressure hoist comprising a cylinder having a piston and provided with inlet and exhaust ports and also a supply-port, 40 a valve governing said ports and having an operating-stem, a casing therefor, a hub secured to the stem and having actuating lever-arms, means for normally holding the valve in lap position and a pair of projecting arms 45 on the hub adapted to contact the casing respectively in full-release and full-application position.

11. A fluid-pressure hoist comprising a cyl-

inder having a piston and provided with inlet and exhaust ports and also a supply-port, 50 a casing connected to the cylinder and having a chamber and a rotary valve therein for governing said ports, said chamber having a score on its inner wall communicating with one of said ports to drain away moisture. 55

12. A fluid-pressure hoist comprising a cylinder having a piston and provided with inlet and exhaust ports and also a supply-port, a valve device governing said ports and having an operating-stem, a casing therefor, a 60 pin mounted on the outside of the casing, a spring coiled around the pin and having its free ends extending across the casing on either side, lever-arms secured to the stem, a horn also secured to the stem, movable there- 65 with and extending between the ends of the spring and a pair of projecting arms also secured to the stem and contacting, and limited in motion by, the pin in the full-application and full-release position of the valve, such 70 pin forming a combined pivot-pin and a stop.

13. A fluid-pressure hoist comprising a cylinder having a piston and provided with a cylinder port or passage 10 and a reservoir port or passage 9, a base or valve-seat 11 secured to the cylinder and having ports 13 and 14 communicating with ports 9 and 10 respectively and an exhaust-port 15, a disk valve 12 having on its inner face port connecting means and working on such seat to govern 80 the ports, a stem for the valve, a casing 12 for such valve having lugs 23, a pin 24 arranged therebetween, a spring having an intermediate spiral portion coiled around the pin and having its ends curved around on 85 either side of the casing and then having its extreme free ends extending parallel, a hub secured to the valve-stem and having lever-arms 28 and 29, and a projecting arm or horn 30 extending between the free ends of the 90 spring intermediate of the lever-arms.

NIELS ANTON CHRISTENSEN.
